UNITED STATES PATENT OFFICE.

RANSOM E. OLDS AND HORACE T. THOMAS, OF LANSING, MICHIGAN, ASSIGNEES TO REO MOTOR CAR COMPANY, OF LANSING, MICHIGAN, A CORPORATION OF MICHIGAN.

GAS-ENGINE.

No. 890,571.

Specification of Letters Patent.

Patented June 9, 1908.

Application filed July 10, 1907. Serial No. 382,976.

To all whom it may concern:

Be it known that we, RANSOM E. OLDS and HORACE T. THOMAS, citizens of the United States, residing at Lansing, county of Ingham, State of Michigan, have invented certain new and useful Improvements in Gas-Engines, and declare the following to be a full, clear, and exact description of the same, such as will enable others skilled in the art to which it pertains to make and use the same, reference being had to the accompanying drawings, which form a part of this specification.

Our invention relates to gas engines, and the object of our improvements is to provide an improved and simplified engine working on the six cycle principle. We accomplish this object in the device illustrated in the accompanying drawing, in which the view is a vertical, central section in elevation.

A is the cylinder; B the crank case; C a piston; D the main shaft; E the connecting rod, and F the crank pin.

G is a gear wheel upon the main shaft D, meshing with a larger gear wheel H upon the cam shaft I.

J is one cam, and K is another cam, upon the shaft I, the offices of which will be hereinafter described.

P is an exhaust port through the wall of the cylinder A, opening into an exhaust pipe or conduit Q. The port P, together with the piston C, constitute the principal exhaust apparatus. The conduit Q communicates with a muffler R.

L is a puppet valve in the conduit between the port P and the muffler R, and M is a stem extending from the valve L and adapted to reciprocate in guides.

N is a spring tending to force the valve stem M downward, and the valve L upon its seat. The cam J acts upon the roller at the lower end of the valve stem M to raise the valve L from its seat.

V is an exhaust passage leading from the upper end of the cylinder A, and S is a valve adapted to close said exhaust passage. The passage V and valve S constituting a second or auxiliary exhaust apparatus.

T, T, is an operating mechanism by which the valve S may be raised by operation of the cam shown in dotted lines, and indicated by the letter K. The inlet valve to the cylinder A is of the ordinary construction, and is operated in the usual way.

2 is an intake valve which may be operated from the shaft I in the usual way, or in any proper way.

The operation of the above described device is as follows:—Ignition having taken place, the piston C is driven downward until it uncovers the port P, at which time the valve L is raised from its seat by the cam J, and the greater part of the products of combustion is exhausted into and through the muffler R. As the piston C rises, it covers the port P, and the valve S is now forced from its seat by the cam K, and the remaining products of combustion are exhausted through the passage V. The passage V communicates with the outer air and not with the muffler. The piston having risen and discharged most of the remaining exhaust gases, begins again to descend, the valve S still remaining open, thus a scavenger charge of air is drawn through the passage V. Having completed its downward stroke, the piston C again rises, the valve S still remaining open, and discharges the scavenger charge taken in on the previous stroke. The valve S now returns to its seat, and the next downward stroke of the piston C draws an explosive mixture into the cylinder A in the usual way, which mixture is compressed when the piston C again rises. Ignition now again takes place, and the cycle above described is repeated.

It will be observed that the passage V serves to discharge the residual products of combustion, and to take in and discharge the scavenger charge, that there is but one valve S in the passage V, and this valve opens and closes but once in each cycle of operation.

What we claim is:

1. In a six-cycle gas engine, an exhaust apparatus adapted to relieve the pressure toward the end of the working stroke, a second exhaust apparatus adapted to convey the products of combustion remaining after the gases under pressure have been exhausted, and means for holding said second exhaust apparatus open for the intake and discharge of the scavenger charge, for the purpose described.

2. A six cycle gas engine, provided with an exhaust apparatus adapted to be opened near the end of the working stroke and with a second exhaust apparatus adapted to remain open during the three strokes following the working stroke.

3. In a six-cycle gas engine, the combination of a cylinder, having a port through the wall thereof, a piston adapted to reciprocate in said cylinder, said port being so located as to be covered by said piston except toward the end of its outer stroke, said engine being provided with a passage V, means for opening and closing the passage V adapted to hold said passage open during the exhaust stroke, and the inlet and discharge of the scavenger charge.

4. A six cycle gas engine, provided with an exhaust apparatus adapted to be opened near the end of the working stroke and hav-

ing a conduit for the exhaust gases, a non-return valve located in said conduit, said engine being also provided with a second exhaust apparatus adapted to remain open during the three strokes following the working stroke.

In testimony whereof, we sign this specification in the presence of two witnesses.

RANSOM E. OLDS.
HORACE T. THOMAS.
